CAR SEAT

John M. Knight, Atlantic Highlands, N. J., Frederick A. Stevenson, New York, N. Y., and Victor Willoughby, Ridgewood, N. J., assignors to American Car and Foundry Company, New York, N. Y., a corporation of New Jersey

Application December 9, 1930, Serial No. 501,004

26 Claims. (Cl. 155—96)

This invention relates to seats and has particular reference to seats for railway cars which are adapted to be revolved in a horizontal plane to face toward either end of the car.

One object of this invention is the provision of a car seat, the seat portion of which is adapted to be first shifted horizontally and then rotated to reverse the position thereof.

Another object of this invention is the provision of a car seat having a horizontally shiftable seat plate carrier which rotatably mounts a seat plate normally maintained in a predetermined position, but which may be rotated relative to the seat plate carrier to reverse the position of the seat.

A further object of this invention is the provision of a railway car seat having a horizontally shiftable seat plate carrier which latter carries a seat plate adapted for rotation relative thereto, and means for retaining the seat plate in proper position with respect to the seat plate carrier.

Other objects and advantages of this invention will be apparent from the following description, taken in conjunction with the accompanying drawings in which:

Fig. 1 is a side elevation of the car seat, certain parts being broken away and other parts being shown in section, the figure also showing, diagrammatically, a portion of the seat body frame.

Fig. 2 is a top plan view of the seat of the present invention with the seat body removed.

Fig. 3 is a sectional view on the line 3—3, Fig. 1.

Fig. 4 is a top plan view of the seat of the present invention, with the seat plate and seat body removed to clearly show the seat plate carrier.

Fig. 5 is a detail sectional view of the seat plate carrier and seat plate showing a modified form of retaining means for the seat plate.

Fig. 6 is a detail sectional view showing the seat plate carrier and seat plate and another modification of retaining means for the seat plate.

Fig. 7 is a sectional view showing a modified form of connecting the seat plate to the seat plate carrier.

Fig. 8 is a fragmentary sectional view of the seat of the present invention showing a modified form of supporting means for the seat plate carrier to permit the same to shift horizontally, and

Fig. 9 is a sectional view on the line 9—9, Fig. 5, ure 1.

Referring now more particularly to the drawings in which similar characters of reference designate similar parts in the several views, the seat of the present invention includes a pedestal indicated generally at A which is more or less of box shape and comprises the side and end walls 2 and 4 respectively and a flared base 6 defining an attaching flange for securing the seat to a support. The pedestal is provided with a top wall 8 across which are secured spaced brackets 10, the ends of which extend beyond the side walls 2 and are provided with bearing portions 12 for supporting guide rods 14 arranged parallel to the side walls 2 as shown more clearly in Fig. 4.

Supported for sliding movement on the guide rods 14 which serve as tracks is a body supporting device formed of connected elements comprising a seat plate carrier 16 and a seat plate 28.

The seat plate carrier is preferably of the form shown more clearly in Figs. 1 and 4 and

comprises a substantially rectangular frame 18 having end rails 19 and 21 respectively, said frame being further provided with bearings 20

slidably mounted on the guide rods 14 whereby

the seat plate carrier is supported. The seat plate carrier also includes a vertically arranged

circular flange 22 and an upwardly extending

annular guide rib 24 spaced inwardly from the

flange 22 and concentrically arranged with respect to the latter; the flange 22 and guide rib

24 defining therebetween an annular recess 24'

into which the depending annular flange 26 of

the seat plate extends to be supported; the flange

26 fitting around the guide rib 24 and the latter

constituting a hub which defines the axis of rotation of the seat plate as will be apparent

from the following description. The recess 24'

is also adapted to receive grease or other suitable lubricant. As clearly shown in Fig. 1, the flange 26 is offset from the remainder of the seat plate 28 thereby providing a shoulder 29 the purpose of which will be hereinafter described. As

shown clearly in Fig. 1, the rib 24 is of substantially the same height as the depending flange 24'

26 of the seat plate and serves to support a retaining element which, in Fig. 1, is shown as a

continuous ring 30 secured to the rib 24 by suitable fasteners 32 and overlapping the shoulder

29 to retain the seat plate against vertical shifting relative to the seat plate carrier.

The top 8 of the pedestal is provided with an elongated opening 34 into which extends a projection 36 formed with and depending from the

seat plate carrier; said projection being prefer-

ably stiffened by ribs 38. Inside the pedestal and adjacent one end wall 4 thereof is a diaphragm 40 to which is secured a foot pedal 42 of angle shape, leg 44 thereof being pivotally secured to a link 46 which extends through projection 36 and has a nut 48 secured to the end thereof. The nut 48 carries an eye 50 to which one end of a spring 52 is connected. The opposite end of spring 52 is secured to a rod 54 extended through a slotted angle 56 and through the adjacent end wall 4 of the pedestal and retained in position by a nut 58.

In order to permit assembly of the spring 52 and rod 54, and also to permit access to the interior of the pedestal should repairs be necessary, the end wall 4 opposite the foot pedal 42 is provided with an opening 59 which is normally closed by a plate 61 having a pocket 63 formed therein which covers the nut 58. It has been found advisable also to cover the guide rods, the brackets and carrier bearings and to that end shields 65 are provided as clearly shown in Figs. 2, 3 and 4.

The guide rod bracket 10 adjacent the spring 25 52 is provided with a vertical stud 60 approximately midway between the ends thereof and said stud serves to mount a roller 62 the purpose of which will be presently described. This stud 60 is formed integral with the guide rod bracket 10 30 and a portion thereof defines an abutment 67 against which the contiguous end rail 19 of the seat plate carrier is adapted to contact to limit the shifting of said carrier in one direction as hereinafter more fully described. The opposite bracket 10 is provided with an abutment 69 for 35 limiting horizontal shifting of the carrier 16 in the opposite direction as hereinafter described.

As before mentioned the seat of the present invention is adapted to be rotated in a horizontal plane and this results from the particular arrangement of parts and the construction of the seat plate and its association with the seat plate carrier. As shown clearly in the drawings the seat plate comprises a circular portion 64 from 40 which front and rear bars or arms 66 and 68 respectively extend, said arms serving to support the seat body frame or cushion frame 70 of the seat. Formed with the seat plate at diametrically opposite points are stops 72 the effective 45 areas 73 thereof being arranged in substantially the same vertical plane. In the instance illustrated in the drawings the stops 72 are shown as extending from and formed integral with the rear arm 68, though obviously this is merely by way 50 of example, as the construction shown is susceptible of various modifications. Arranged beneath the front arms 66 is a horizontally extending arcuate roller flange 74 the ends of which terminate adjacent the stops 72 and define with 55 said stops, slots 76 in which the before mentioned roller 62 is arranged when the seat is in either of its normal positions. The roller 62 does not function as a means for limiting the shifting movement of the seat plate carrier. Horizontal 60 shifting of the seat plate carrier is limited, as before mentioned, by contact of the end rails 19 and 21 with the abutments 67 and 69. The roller 62 serves to prevent rotation of the seat plate ring member 26. As shown clearly in Fig. 9, when the 65 seat plate carrier is in its normal position a distinct space 63 is present between the roller and the ring member 26.

The particular means for retaining the seat plate in position is susceptible of many variations, of which several are shown in the drawings.

In Fig. 5 the inner surface of the rib 24 is threaded to receive an angle shaped retainer ring 78, lug 80 of which overlies the shoulder 29 of the flange 26. In Fig. 6 a plurality of retainers are provided, the same comprising plates 82 secured to the rib 24 and overlying the shoulder 29. In Fig. 7 the outer surface of rib 24 threadedly receives the flange 26 of the seat plate whereby to support the seat plate and retain the same against relative vertical shifting with respect to the seat plate carrier. The connection of the seat plate and the seat plate carrier in Fig. 7, while being a threaded one is nevertheless of such a character as to permit rotation of the seat plate relative to the carrier to obtain a reversal of the position of the seat body.

Fig. 8 discloses a modification of the means for permitting shifting of the seat plate carrier and seat plate. In this instance the guide rods 14 are eliminated and the side walls 2 of the pedestal are provided with brackets 84 riveted or otherwise secured to the pedestal. The seat plate carrier in this instance is provided with supporting portions 86 which rest on the brackets 84 and are slidably thereon. The brackets are generally Z-shaped in cross section and the upper edges thereof are inturned as at 88 to overlap the supporting portions 86.

From the above description it is believed that the construction of the seat of the present invention will be fully apparent to those skilled in the art. In operation, assuming the seat to be in the position illustrated in Fig. 2 and it is desired to reverse the position thereof, the foot pedal 42 is depressed whereupon the seat plate carrier and seat plate with the associated seat body will be shifted horizontally on the guide rods 14 shown in Figs. 2 and 4 or on the brackets 84 shown in Fig. 8 until the end rail 21 of the frame of the seat plate carrier contacts with the abutment 69 formed on one of the brackets 10, as heretofore described. This horizontal shifting will move the seat plate to a position such that the roller 62 will be freed from the slot 76 and the seat may then be rotated in a clockwise direction (see Fig. 2), the roller 62 riding along the roller flange 74 until the seat body is reversed and the opposite slot 76 aligned with the roller 62 whereupon the spring 52 will serve to return the seat plate carrier, seat plate and seat body to its normal position. It will be obvious that the rib 74 serves to retain the seat plate carrier and seat plate in horizontally shifted position during rotation of the seat plate until the seat is reversed, thereby eliminating the necessity of retaining the foot pedal 42 in depressed position during the time of rotation; the foot pedal therefore being only utilized to initially shift the seat plate carrier and seat plate to disengage the roller 62 from the slot 76.

The drawings herein illustrate the preferred embodiments of the invention, but it is to be understood that they are for illustrative purposes only and various changes in the form and proportions of the construction may be made within the scope of the appended claims without departing from the spirit of the invention.

What is claimed is:

1. In a shiftable and rotatable seat having a pedestal, a seat plate carrier slidably supported by the pedestal, a seat plate rotatably mounted on the carrier, stop means on the pedestal normally in cooperative relation with the seat plate to restrain the latter against rotation, and lever actuated means connected to the carrier and operable

- to shift the latter and said seat plate relative to the pedestal to free the seat plate from the stop means.
2. In a shiftable and rotatable seat having a base, a seat plate carrier shiftably supported by the base and arranged above the upper surface thereof, a seat plate supported by and rotatably mounted on the carrier, detachable means connected to the carrier and engaging the seat plate for retaining the latter against shifting relative to the carrier, a restraining element on the base normally in cooperative relation with the seat plate to prevent rotation of the latter, and lever means connected to the said carrier operable to shift the latter and the seat plate relative to the base to free the seat plate from the restraining element.
3. In a shiftable and rotatable seat having a pedestal, a seat plate carrier, tracks secured to the pedestal along opposite sides thereof, bearing members attached to the carrier and engaging the tracks to support said carrier for longitudinally shifting movement, said carrier being provided with an annular supporting surface and an annular hub adjacent the said supporting surface, a seat plate encircling said hub and rotatably mounted on the supporting surface, stop means on the pedestal adapted to cooperate with the seat plate to normally restrain the latter against rotation, said means including an abutment normally in contacting relation with the seat plate carrier, lever means for moving said carrier on the tracks whereby said carrier shifts the seat plate out of engagement with the stop means to free said seat plate for rotation from one position to another, and yielding means for returning the carrier and seat plate to normal position after shifting and rotation of said seat plate, the abutment contacting the said carrier to limit the return movement thereof.
4. In a seat, a pedestal, spaced track supporting brackets secured to the upper surface of the pedestal, a pair of tracks supported by the brackets, a seat plate carrier, bearings attached to the said carrier and slidably engaging the tracks to support the carrier for longitudinal shifting movement, said carrier including an annular hub, a seat plate supported by the carrier and encircling the hub, the latter defining an axis of rotation for said seat plate, a stud secured to one of said brackets and with which the carrier normally contacts, a roller carried by said stud and normally cooperating with the seat plate to restrain the latter against rotation, lever means for shifting said carrier longitudinally of the pedestal out of contact with said stud whereby to shift the seat plate to free the latter from its cooperative relation with the roller to permit rotation of said seat plate on the carrier, and resilient means connected to the pedestal and seat plate carrier for returning said carrier and its associated seat plate to normal position after shifting, said carrier contacting with said stud whereby the latter limits the extent of return movement of said carrier.
5. In a shiftable and rotatable seat having a pedestal, a seat plate carrier slidably supported by the pedestal, a seat plate rotatably mounted on and secured against vertical shifting relative to the carrier, and manually operable means supported by the pedestal and connected with the carrier for sliding the carrier and seat plate horizontally.
6. In a shiftable and rotatable seat having a pedestal, a seat plate carrier horizontally shift-
- able on the pedestal, a seat plate rotatably mounted on the carrier, retaining means for preventing shifting of the seat plate relative to the carrier, a locking element carried by the pedestal and with which the seat plate is normally engaged in such a manner as to prevent rotation of the seat plate on the carrier, and actuating means connected to the carrier and operable for shifting the carrier and the seat plate horizontally to disengage the seat plate from the locking element.
7. In a shiftable and rotatable seat having a pedestal, track members carried by the pedestal, a seat plate carrier mounted on and shiftable along the track members, a slotted seat plate rotatably mounted on said carrier, a locking element carried by the pedestal and normally arranged in a slot of the seat plate, and means on the pedestal connected to the carrier and operable for shifting the carrier and seat plate horizontally relative to the pedestal to disengage the seat plate from the locking means.
8. In a shiftable and rotatable seat having a base, a seat body supporting device shiftably supported by the base and including a rotatable seat plate, locking means on the base normally in cooperative relation with the seat plate to prevent rotation of the latter, lever means connected to the seat body supporting device and operable to shift the latter relative to the base to disengage the seat plate from the locking means, the seat plate being adapted to contact with the locking means during rotation of the seat plate to retain the seat body supporting device in shifted position during such rotation.
9. In a seat, a pedestal, a seat plate carrier supported by the pedestal, a seat plate connected to said carrier and rotatably mounted thereon, cooperating stop elements on the pedestal and seat plate adapted to normally restrain the seat plate against rotation, the stop element on said pedestal being provided with an abutment with which said carrier normally contacts, and lever actuated means supported by the pedestal and connected to the carrier, said lever actuated means being operable to shift said carrier and seat plate horizontally relative to the pedestal to disengage the before mentioned cooperating stop elements from each other.
10. In a seat, a pedestal, supporting rails secured to the pedestal, a two-part seat body supporting device supported by the rails, and lever means connected to the body supporting device for shifting the latter on the rails, one of the parts of said seat body supporting device being rotatable relative to the other.
11. In a seat, a pedestal, horizontally disposed supporting rails carried on the pedestal, a two-part seat body support slidably supported on said rails for movement thereon in a uniform horizontal plane and having one part thereof rotatably mounted on the other part, and means on the pedestal normally in cooperative relation with said rotatably mounted part in such a manner as to retain the latter in predetermined position.
12. In a seat, a pedestal, combined rail supporting brackets and stops secured to the pedestal, rails carried by said brackets, a seat body supporting device slidably mounted on the rails and adapted to cooperate with the stops to limit its sliding movement.
13. In a slidable seat having a pedestal, supporting elements arranged externally of and secured to the pedestal, a seat plate carrier slidably mounted on the supporting elements, a seat

- plate mounted on the seat plate carrier, locking means on the pedestal with which the seat plate normally engages to be held against movement relative to the seat plate carrier, and lever actuated mechanism supported by the pedestal and connected to the seat plate carrier, said mechanism being operative to shift the seat plate carrier and seat plate on the supporting elements to free the seat plate from the locking means.
10. 14. In a shiftable and rotatable seat having a pedestal, a seat plate carrier supported by the pedestal and constituting a seat plate support, a seat plate rotatably mounted on the seat plate carrier, a retaining element in cooperative relation with the seat plate carrier and seat plate adapted to restrain the seat plate against vertical shifting relative to the seat plate carrier, a locking element supported by the pedestal and normally in engagement with the seat plate to restrain the latter against rotation, and actuating means supported by the pedestal and connected to the seat plate carrier, said means being operative to shift the seat plate carrier and seat plate relative to the pedestal to free the seat plate from the locking element.
15. 15. In a shiftable and rotatable seat having a pedestal, track members secured to opposite sides of the pedestal, a seat plate carrier mounted on and capable of shifting along the track members and provided with a supporting surface, a seat plate rotatably mounted on the supporting surface and having oppositely arranged outwardly opening slots, a locking element on the pedestal normally arranged in one of said slots, and actuating mechanism secured to the pedestal and connected with the seat plate carrier, said mechanism being operative to shift the seat plate carrier and seat plate horizontally to release the seat plate from the locking element.
20. 16. In a shiftable seat having a pedestal, a seat plate carrier supported by the pedestal and capable of horizontal shifting relative thereto, said seat plate carrier being provided with an annular supporting surface, a seat plate, an offset annular flange depending from the seat plate and arranged on the supporting surface, retaining means secured to the seat plate carrier and lapping the offset flange of the seat plate to restrain the latter against vertical shifting relative to the seat plate carrier, and actuating means connected to the seat plate carrier for shifting the latter and its associated seat plate horizontally relative to the pedestal.
25. 17. In a shiftable and rotatable seat having a pedestal, a seat plate carrier horizontally shiftable on the pedestal, a seat plate rotatably mounted on the carrier, retaining means for preventing shifting of the seat plate relative to the seat plate carrier, a locking element secured to the pedestal and normally engaged with the seat plate to prevent rotation of the seat plate relative to the seat plate carrier, actuating means for shifting the seat plate carrier and seat plate horizontally to disengage the latter from the locking means, and a projecting flange on the seat plate adapted to engage the locking means during rotation of the seat plate.
30. 18. In a shiftable and rotatable seat having a pedestal, track members carried by the pedestal, a seat plate carrier mounted on and shiftable along the track members, said seat plate carrier having an annular supporting surface, a seat plate, an annular supporting element formed with the seat plate and engaging the annular supporting surface to mount the seat plate for
35. rotation, oppositely arranged stops secured to the seat plate, an arcuate flange projecting from the seat plate and having its ends arranged in spaced relation with respect to said stops to define with said stops oppositely extending horizontal slots, a locking element supported by the pedestal and normally arranged in one of said slots, and means on the pedestal connected to said seat plate carrier and operable for shifting the seat plate carrier and seat plate horizontally relative to the pedestal to disengage the seat plate from the locking element whereby to permit rotation of the seat plate.
40. 19. In a shiftable and rotatable seat having a pedestal, a seat plate carrier supported by the pedestal and having an upwardly extending annular threaded rib, a seat plate threadedly secured to said rib, means secured to the pedestal and normally engaged with the seat plate to restrain the latter against rotation and lever actuated means for shifting the seat plate carrier horizontally to cause the seat plate to be released from the before mentioned restraining means.
45. 20. In a shiftable and rotatable seat having a pedestal, spaced brackets secured to the pedestal and having their ends extended beyond the side walls thereof, track elements paralleling the side walls and supported by the brackets, a seat plate carrier slidably supported by the track elements, a seat plate rotatably mounted on the carrier, locking means with which the seat plate is normally engaged to prevent rotation of said seat plate relative to the seat plate carrier and shiftable means secured to the pedestal and connected to the seat plate carrier for moving the carrier horizontally to disengage the seat plate from the locking means.
50. 21. In a shiftable and rotatable seat having a pedestal, a seat plate carrier, means on the pedestal supporting the seat plate carrier for horizontal shifting movement relative to the pedestal, a seat plate rotatably mounted on the seat plate carrier, locking means secured to the pedestal and with which the seat plate is normally engaged to be restrained against rotation relative to the seat plate carrier, actuating means connected to the seat plate carrier and operative to shift the seat plate carrier and seat plate horizontally to release the seat plate from the locking means, and a flange on the seat plate adapted to engage the locking means during rotation of the seat plate to restrain the seat plate carrier and seat plate against returning to normal position until completion of rotation.
55. 22. In a shiftable and rotatable seat having a pedestal, a seat plate carrier, means on the pedestal supporting the seat plate carrier for horizontal shifting movement relative to the pedestal, a seat plate supported wholly by and rotatable on the seat plate carrier, stop means on the pedestal with which the seat plate cooperates to normally restrain the latter against rotation, said means including an abutment with which said seat plate carrier normally contacts to limit shifting movement of the seat plate carrier in one direction, lever means for shifting the seat plate carrier relative to the pedestal to release the seat plate from its rotation restraining means and resilient means connected to the pedestal and the seat plate carrier for returning said carrier and its associated seat plate to normal position.
60. 23. In a seat, a pedestal, combined rail supporting brackets and stops secured to the pedestal, rails carried by said brackets, a seat body
65. 70. 75.

5 Supporting device slidably mounted on the rails and adapted to cooperate with the stops to limit its sliding movement, said device having a rotatable portion adapted for attachment to a seat body.

24. In a seat, a pedestal, supporting rails on the pedestal, a seat plate, a seat plate carrier slidably mounted on the rails and on which the seat plate is rotatably supported, stop members 10 for limiting sliding movement of the said seat plate carrier, and means on the pedestal normally cooperating with the seat plate to restrain the latter against rotation.

25. In a shiftable seat having a pedestal, a 15 seat plate carrier supported by the pedestal and capable of horizontal shifting relative thereto, said seat plate carrier being provided with an annular supporting flange, a seat plate, an offset annular flange depending from the seat plate and

arranged on the supporting flange, retaining means secured to one of said flanges and overlapping the other flange to restrain the seat plate against vertical shifting relative to the seat plate carrier, and actuating means for shifting the 5 seat plate carrier and its associated seat plate horizontally relative to the pedestal.

26. A car seat base comprising a pedestal, a slide supported by the pedestal and laterally movable in a uniform horizontal plane over an upper 10 face thereof, a seat support rotatably mounted on said slide and bearing directly on an upper face thereof whereby it is supported, and means for locking said support against rotation, said locking means being releasable by lateral move- 15 ment of said slide.

JOHN M. KNIGHT.
